PAUL R. WENDELL

INVENTOR

BY *Victor J. Evans*

ATTORNEY

UNITED STATES PATENT OFFICE.

PAUL R. WENDELL, OF CHICAGO, ILLINOIS.

METAL PACKING.

Application filed February 13, 1921. Serial No. 444,455.

To all whom it may concern:

Be it known that I, PAUL R. WENDELL, a citizen of the United States, residing at Chicago, in the county of Cook and State of Illinois, have invented new and useful Improvements in Metal Packing, of which the following is a specification.

This invention relates to metal packing for use in stuffing boxes and various types 10 of machinery, and an object of the invention is to provide a yieldable, noncompressible metal packing which will yield, under compression, to securely pack or seal a joint, but which will not become hardened or compressed under successive applications of 15 power or pressure there against.

Another object of this invention is to provide a yieldable, noncompressible packing which will readily lend itself to shaping for 20 providing the most practical and desired shape of packing depending upon the use to which it is to be put.

A further object of this invention is to provide a metal packing which will require 25 only a simple process in the forming and shaping thereof.

Another object of this invention is to provide a metal packing which is formed of sheets of pliable metal having one surface 30 covered or coated with a liquid after which the pliable sheets of metal are crimped or crushed to provide irregular shapes to the metal in cross section and also provide pockets of irregular shape within the body of the 35 packing formed by the crushing of the sheet metal to prevent compressing of the packing.

Other objects of the invention will appear in the following detailed description and in 40 the accompanying drawing wherein:

Fig. 1 is a perspective view of one form or shape of the packing.

Fig. 2 is an edge elevation of a sheet of pliable metal showing it coated with liquid 45 prior to the crushing of the metal and illustrating the first step in the process or method of forming the packing.

Fig. 3 is an edge elevation of the pliable sheet metal partially crushed into packing 50 shape and illustrating the second step in the method of forming the metal packing.

Fig. 4 is a section through a modified form of the packing.

Referring more particularly to the drawing, it is to be understood that while the 55 piece of the metal packing shown in Fig. 1 of the drawing is rectangular in shape, that the improved packing may be made in any shape, such as cylindrical, polygonal in cross section, or any shape desired, depending 60 upon the place it is to be used and the work to be performed by it.

In forming the metal packing a sheet 1 of pliable metal, such as sheet Babbitt metal or the like, is first coated with a liquid such as 65 cylinder or lubricating oil as shown at 2 in Fig. 2 of the drawing, after which the sheet of pliable metal is bunched or crushed, as illustrated in Fig. 2 of the drawing to provide irregular shapes to the sheet and to 70 provide a regular outer surface to the composite piece of packing formed by the crushing of the sheet, the outer shape depending upon the use to which the packing is to be put. The crushing of the sheet of pliable 75 metal from two opposite edges will provide, besides irregularities in the shape of the metal, irregular pockets within the formed packing in which the liquid 2 will be confined providing a yieldable, noncompressible packing. Any suitable type of liquid 80 may be employed without departing from the spirit of this invention. If it is so desired the formed piece of packing may be encased in a suitable shell as illustrated at 3 85 formed of a sheet of pliable metal, preferably of the same type as the sheet 1.

The formation of the irregularly shaped pockets in the packing, which pockets will have their ends closed and will not extend 90 throughout the entire length of the packing will prevent the liquid from oozing out of the ends of the packing, however, in forming a continuous piece of packing it may be desirable to provide pockets therein which 95 are comparatively regular and extend throughout the length of the continuous piece of packing and such a modified form is illustrated in Fig. 4 of the drawing.

It is, of course, to be understood that the 100 invention may be constructed in various other manners and the parts associated in

different relations and, therefore, I do not desire to be limited in any manner except as set forth in the claim hereunto appended.

Having thus described my invention what 5 I claim is:

A metal packing comprising a core formed of pliable sheet metal crushed together to form irregular shapes and pock-

ets, a lubricant in said pockets and an outer casing of pliable sheet metal of the same 10 type as the core and folded about the crushed pliable sheet metal core to entirely enclose the same.

In testimony whereof I affix my signature.

PAUL R. WENDELL.
